POWER SUPPLY FOR AN ELECTRONIC FLASH

Harry L. Parker, Whitestone, N.Y.

Application February 20, 1959, Serial No. 54,694

Term of patent 14 years

(Cl. D61—1)

Fig. 1.

Fig. 1 is a perspective view of a power supply for an electronic flash, showing my new design;

Fig. 2 is a top plan view;

Fig. 3 is an opposite side elevational view; and

Fig. 4 is a front elevational view, the rear being substantially a mirror image thereof.

The fragmentary broken line showing of a carrying strap in Fig. 1 is for illustrative purposes only.

I claim:

The ornamental design for a power supply for an electronic flash, substantially as shown and described.
